[57] CLAIM

The ornamental design for a wall-mounted support, as shown and described.

DESCRIPTION

FIG. 1 is a front elevational view of a wall mounted support showing my new design in the closed position; FIG. 2 is a reduced rear elevational view thereof; FIG. 3 is a side elevational view thereof; FIG. 4 is a reduced top plan view thereof, the bottom being identical;

FIG. 5 is a reduced front perspective view thereof, with a horizontal and a vertical member in the extended position.

FIG. 5
